United States Patent Office

Des. 212,679
Patented Nov. 12, 1968

212,679

CONTAINER FOR POURABLE MATERIAL

Jacques Gaspard Honoré Ollier, 17 Rue du General Henrion Bertier, Neuilly-sur-Seine, France; Georges Frédéric Grosshans, 53 bis Rue de Boulainvilliers, Paris, France; and Robert Gaston Masson, 10 Blvd. de Courbevoie, Neuilly-sur-Seine, France

Filed Sept. 27, 1966, Ser. No. 4,054

Term of patent 14 years

(Cl. D9—219)

Fig.1.

Fig.3.

Fig.2.

Fig.4.

FIGURE 1 is a side elevational view of a container for pourable material showing our new design;

FIGURE 2 is a top plan view thereof;

FIGURE 3 is a sectional view taken on the line III—III of FIGURE 1; and

FIGURE 4 is a bottom plan view thereof.

We claim:

The ornamental design for a container for pourable material, as shown.
